Primary Examiner — Cynthia Ramirez(74) *Attorney, Agent, or Firm* — Christie, Parker & Hale, LLP(57) **CLAIM**

The ornamental design for an extrusion for climbing monorail, as shown and described.

DESCRIPTION

FIG. 1 is an end view of an extrusion for climbing monorail showing my new design; and,

FIG. 2 is a perspective view thereof.

The broken lines on the extrusion indicate that no specific length is claimed.
